Inventor

August M. Seaver

By Frank E. Liverance, Jr.
Attorney

UNITED STATES PATENT OFFICE.

AUGUST M. SEAVER, OF GRAND RAPIDS, MICHIGAN.

SPARK-PLUG CLEANER.

Application filed January 9, 1922. Serial No. 528,074.

To all whom it may concern:

Be it known that I, AUGUST M. SEAVER, a citizen of the United States of America, residing at Grand Rapids, in the county of Kent and State of Michigan, have invented certain new and useful Improvements in Spark-Plug Cleaners; and I do hereby declare the following to be a full, clear, and exact description of the invention, such as will enable others skilled in the art to which it appertains to make and use the same.

This invention relates to a spark plug cleaner. It is well known that in the operation of internal combustion engines, the spark plugs which are used for igniting the explosive charges in the cylinders of the engine, many times become encrusted with what is known as carbon. The carbon deposit on the plugs serves to render the same more or less ineffective for the production of the ignition sparks made by the jumping of the electric current across a gap in an electric circuit of which each plug is a part by reason of a more or less completion of the circuit through the carbon. Accordingly, it is necessary that the plugs be kept clean and it is very common to remove the spark plugs from the engine and clean the carbon therefrom.

My invention is directed to the production of a very simple yet effective cleaner for spark plugs and one with which spark plugs may be very quickly freed from the carbon deposits thereon, particularly on the inner sides of the lower end portion of a plug from which it is usually hard to remove the carbon without taking the plug apart, a process to be avoided if possible. It is a primary object and purpose of my invention to construct a spark plug cleaner by means of which the above described ends are effectively attained. A further object of the invention is to make a device of this character very cheaply so that the same may be marketed at low cost. Various other objects and purposes than those stated will appear as understanding of the invention is had from the following description, taken in connection with the accompanying drawing, in which,

Fig. 1 is a front elevation of the spark plug cleaner of my invention.

Fig. 2 is a side view thereof, and

Fig. 3 is a side elevation showing the

cleaner in conjunction with a spark plug. 55 Like reference characters refer to like parts in the different figures of the drawing.

In the construction of the spark plug cleaner, a length of wire is coiled at its 60 middle into a circular coil, indicated at 1, one end of the coil being extended downwardly, as shown at 2 in Figs. 1 and 2, for a short distance and then flattened into a relatively long and thin wider blade 3, sub- 65 substantially rectangular in cross section. The other end of the coil is likewise extended downwardly for a short distance, as shown at 4, and is then similarly flattened into a second relatively long and thin blade 5. 70 The blades 3 and 5 are nearly if not quite parallel, preferably, however, diverging somewhat as they extend downwardly.

This spark plug cleaner is very useful in connection with the removal of carbon from 75 the inner surfaces of the shells of spark plugs. The method of using is shown in Fig. 3, the spark plug outer shell 6 with its exteriorly threaded lower end 7 and centrally located insulating porcelain 8 being 80 of common construction with an annular space between the porcelain and the part 7 in which carbon collects. The blades 3 and 5 are easily inserted into this annular space being sprung together and on account of 85 the tendency for the same to spring outwardly and back to original position the outer sides of the blades bear firmly against the inner sides of the shell end portion 7. On turning the device as a whole back and forth about the longitudinal axis of the spark plug, the carbon deposit on the inner sides of the end portion 7 of the shell is 90 very quickly and completely scraped off and the plug left in clean condition. The blades 95 3 and 5 having right angular corners, when moved back and forth as described bite into and remove the carbon very thoroughly in a very short time. The material from which the cleaner is made may be spring wire, 100 though there is no necessity that it shall be of such particular material, cleaners made from relatively soft wire proving very satisfactory though not as durable as those of better material.

This construction of spark plug cleaner is simple in construction, can be readily manufactured at low cost and is especially

effective in use. It is readily placed on a key ring or chain, the same passing through the coil at 1 so as to be always available when needed.

5 I claim:

A spark plug cleaner formed from a single length of material bent at its middle

portion to provide two spaced apart nearly parallel legs, each of said legs at its free end portion being of rectangular cross section to provide a relatively thin blade, substantially as and for the purposes described.

10 In testimony whereof I affix my signature.

AUGUST M. SEAVER.
